[57] CLAIM

The ornamental design for a table-top telephone with cordless receiver, as shown and described.

DESCRIPTION

FIG. 1 is a perspective view taken from the top front and right side of a table-top telephone with cordless receiver showing my design;

FIG. 2 is a perspective view thereof taken from the top back and left side;

FIG. 3 is a top plan view thereof;

FIG. 4 is a perspective view of a portion thereof shown in FIG. 1 with the cordless receiver removed from its housing; and,

FIG. 5 is a bottom plan view thereof.

FIG. 3

FIG. 1

FIG. 5

FIG. 2

FIG. 4
